VALVE

Herbert E. Toelle, Milwaukee, Wis., assignor to
Milwaukee Gas Specialty Company, Milwaukee,
Wis., a corporation of Wisconsin

Application August 7, 1931, Serial No. 555,695

13 Claims. (Cl. 251—132)

This invention relates to valves, particularly to valves for use in connection with gas burners.

More particularly, this invention relates to valves of the type in which the valve element is operated manually to control the flow of gas for the burner. Such valves are commonly provided in the nozzle pipes leading from the gas manifold to feed pipes which are connected to the burners and have opening means for the admission of air, but it is to be understood that the present invention is not to be limited to the particular positioning or use of the valve.

It is well known that in the use of gas ranges, it is sometimes desirable to turn the burner flame down relatively low. This is particularly so where the burner is a simmering burner, or where the regular burner is set to simmer the contents of the vessel on the range.

The present valves for controlling the flow of gas to the burner are subject to the criticism that they may be turned or set down too low or opened insufficiently to maintain the burner flame lighted. Where the burner is set too low or opened insufficiently, the burner flame will be extinguished and the escape of gas will be entailed.

With the devices prior to my invention there is no provision for preventing setting the burner control valve too low, and there is no way of knowing when the setting is too low to maintain the burner lighted.

The present invention provides means for preventing setting of the valve means away from but too close to its seat to maintain the desired supply through the valve, and particularly a sufficient supply of gas to maintain the burner lighted. This is accomplished with the present invention by providing means for automatically closing the valve from positions too near closed position to maintain the desired supply therethrough. The minimum open position in which the valve will remain open may vary under different conditions. In its broader aspects the present invention resides in the provision of a valve having means for automatically closing the valve element where it is opened insufficiently to maintain the desired supply through the valve. More particularly, the present invention provides means for automatically closing the valve from all positions between closed position and a predetermined setting away from closed position, and still more particularly from all positions between closed position and a predetermined setting which will pass the minimum amount of gas for maintaining the burner lighted.

The valve of the present invention cannot be

set too low to maintain the burner lighted and in opening the valve by means of the present invention causes it to be opened at once to a safe minimum value.

Another feature of the present invention resides in the wiping action of the valve on the valve seat, which wiping action keeps the cooperating surfaces of the valve and valve seat clean and assures proper alignment of the same at all times.

Another object is to provide a simple and sturdy construction with few parts.

The invention is illustrated in the accompanying drawing, in which:

Figure 1 is a side elevational view of a valve embodying the present invention;

Figure 2 is an axial vertical section thereof, partially in elevation; and

Figure 3 is a plan view of an arrangement embodying the valve shown in Figures 1 and 2.

Referring to the drawing, the usual gas manifold is indicated at 4. The gas burner is indicated at 1, this burner being fed from the manifold 4 by the usual feed pipe 2, to which air is admitted at 3 in the usual way. Gaseous fuel is lead into feed pipe 2 by way of a valve body 5 and a nozzle tube 18, from the manifold 4.

The valve body 5 is shown having an inlet opening 6, adapted to communicate with the interior of a gas manifold or supply pipe 4. The valve body 5 is provided with threads, shown at 7, for the purpose of securely connecting the valve with this gas supply pipe.

The upper portion of the valve body 5 has a recessed portion, indicated by reference numeral 8, and is provided with an opening 9, through which a valve stem 10 is adapted to pass. The recessed opening 8 is provided with suitable packing 11, which is secured in place by means of a washer 12. The upper end of the control stem 10 has a reduced portion 13, as shown in dotted lines in Figure 2, and a handle 14, of any suitable or desired type, is positioned over the reduced portion 13 of the stem 10 and securely held in place by means of a screw 15 adapted to be threaded into the upper end of the stem 10.

The valve body 5 is provided at its outlet end with a hexagonal flange 16, provided for the purpose of threading the valve body into the gas manifold. Projecting from this flanged portion 16 is an exteriorly threaded nipple 17, to which is secured the tube 18, the restricted outlet 18' of which discharges into the feed pipe 2.

As shown in Figure 2, the valve body 5 is provided at its lower extremity with a threaded

hollow member or plug 20, which is adapted to be threaded into the valve body and which has the gasket 21 for providing a gas tight connection therewith. The upper portion of the plug 20 forms a valve seat 22 for the valve member 23. Secured to and integral with the member 23 is a depending cam portion 24, adapted to project into a recess 25 provided in the plug 20. The plug 20 has an interior chamber 26, 10 which provides an intermediate chamber between the inlet 6 and the outlet chamber 27. A connecting channel 28 is provided in the valve body 5 and leads from a port 29 provided in the plug 20 to the outlet chamber 27. The port 29 15 communicates with the interior or intermediate chamber 26 of the plug member 20, and with the adjacent end of the passage 28.

The valve 23 has a raised portion 30, about which the adjacent end of a coiled spring 31 is 20 arranged for normally maintaining the valve in closed position. The other end of the spring 31 bears against the washer 12 of the packing gland.

Cam member 24 is provided at its lower end with a cam portion or surface 32. As shown, the 25 cam portion 32 cooperates with a pin 33, suitably threaded, as by means of screw 34, into the bottom of the plug member 20. It is to be understood that two such cam surfaces 32 may be provided on opposite sides of the cam member 24 for 30 the purpose of preventing unequal stresses to be set up in the valve during rotation thereof.

When the valve is in closed position, as shown in Figure 2, the pin 33 abuts against the vertical portion 35 extending from the cam surface. As 35 the valve is rotated in a counter-clockwise direction (Fig. 2) by means of the handle 14, the pin 33 engages the cam surface shown at 36, and the valve begins to open. As long as the valve is not opened to a position where the pin passes 40 the point 37 of the cam portion, release of the handle 14 will cause the valve to snap to closed position, due to the spring 31 and the relatively sharp inclination of the cam surface 36. As the valve is further rotated in a counterclockwise direction, the pin 33 engages in the slightly grooved portion 38 of the cam surface. It is at this point 45 that the safe minimum open position of the valve is provided.

As the valve is rotated in a counter-clockwise direction beyond this point, the pin 33 tends to 50 force the cam and associated valve portion upwardly against the pressure of the spring 31, to the full open position of the valve. Upon closing of the valve, the pin member again reaches the grooved portion 38 of the cam surface, and the valve may be left in this position if it is to be desired that the burner flame burn relatively low, as, for example, for the purpose of simmering the 55 contents of the vessel thereon. As soon as the point 37 of the cam surface passes the pin 33 in the closing movement of the valve, the valve, due to the sharp inclination of the cam surface 36, is closed automatically by the spring 31 and remains closed until, in the opening movement 60 of the valve, the sharply inclined surface 36 is moved past the pin 33. By threading the screw 34 inwardly or outwardly with respect to member 20, the safe minimum open position of the valve 65 may be varied as desired, depending upon the fuel used and other considerations. If the screw is threaded inwardly, the pin 33 is raised, and consequently the valve member will not be maintained in open position until it has attained a 70 correspondingly raised position. Similarly, if the 75

screw is threaded outwardly, the safe minimum open position of the valve member will be at a point such that a smaller quantity of fuel will flow through the valve at this position. Thus, adjustment of this screw will determine the quantity of fuel flowing through the valve at the safe minimum open position.

In this manner, when the attendant attempts to close the valve beyond a safe value, the valve 10 automatically slides downward to fully closed position by reason of the sharp depression in the cam surface. In the same manner, in opening the valve, it will not remain open until the sharply inclined surface is moved past the pin 33 and this assures opening to the desired minimum 15 value.

In the particular valve construction shown there is some clearance between the valve element 23 and the pin 33 as indicated at 40. This permits turning movement of the valve member on its seat before the valve begins to open and after the valve is closed, and this wiping action 20 wipes the cooperating surfaces to maintain them free of foreign matter, thereby assuring a gas tight closure and proper alignment at all times. 25

It is to be understood that when the valve is opened beyond engagement of the grooved portion 38 with the pin 33 or beyond minimum open position, the gradual inclination of the cam portion 32 permits the valve to remain in 30 any position of cooperation of this surface 32 with the pin 33, and, therefore, in any open position beyond the minimum setting.

I do not intend to be limited to the exact details shown and described. 35

I claim:

1. In combination, a valve member, a seat for said valve member, means yieldingly pressing the valve member toward said seat, and inter-engaging cam means for opening said valve member against yieldingly pressing means by turning movement of the valve member, said cam means including a camming surface, adapted to release said yieldingly pressing means so that said means will close the valve member automatically from position away from but too close to said seat to maintain a desired minimum flow through the valve, and also including a surface adapted to cam said valve member to full open position, one part of said cam means being 50 adjustable to vary the position of said valve member in accordance with the minimum flow of fuel desired through said valve.

2. In a valve, a valve body having inlet and outlet openings therein, a hollow plug in said valve body communicating with the inlet and outlet openings and having a valve seat, valve means for seating on said seat, cam means integral with said valve means, and means carried by said plug for engaging said cam means to open the valve upon actuation of said cam means. 55

3. In a valve, a valve body having inlet and outlet openings therein, a plug member in said valve body forming a chamber therein communicating with said inlet and outlet openings, 65 valve means seating on said plug to close said chamber from the inlet opening, cam means carried by said valve means and positioned in said chamber, and means for engaging said cam means to open said valve upon actuation of said 70 cam means.

4. In a valve, a valve body having a valve seat therein, valve means cooperating therewith, means for yieldingly closing said valve means upon said seat, a cam member carried by said 75

- valve means, means positioned in said valve body for actuating said cam member to open the valve when said valve means is moved in one direction, said cam member having the portion of its camming surface initially engaged by said cam member actuating means adapted to effect the release of said yieldingly closing member to permit closing of said valve means thereby until a minimum open position has been reached, said cam member having the remaining portion of its camming surface engageable by said cam member actuating means to move said valve means into intermediate positions between said minimum open position and full open position and to maintain it in said positions.
5. In a valve, a valve body having inlet and outlet openings, a valve member, cam means carried by said member, a recessed plug in said valve body providing an intermediate chamber between said inlet and outlet openings and also providing a seat for said valve member, and a pin carried by said plug engaging said cam means upon rotation of said valve member.
6. In a valve, a valve body having inlet and outlet openings therein, a valve member, cam means integral with said valve member, a hollow plug in said valve body providing an intermediate chamber between said inlet and outlet openings and forming a seat for said valve member, said cam means extending into said chamber, and an adjustable and removable pin carried by said plug and adapted to engage said cam means upon rotation of said valve member.
7. In a valve, a valve body having inlet and outlet openings therein, a valve member, cam means integral with said valve member, a hollow plug in said valve body providing an intermediate chamber between said inlet and outlet openings and forming a seat for said valve member, and an adjustable pin carried by said plug and adapted to engage said cam means upon rotation of said valve member, said pin and cam means lying wholly within the chamber formed by said plug.
8. In a valve, a valve body having inlet and outlet openings, a valve member, cam means disposed below and integral with said member, a recessed plug in said valve body providing a valve seat, an adjustable and removable pin carried by said plug and adapted to cooperate with said cam means, said pin having lost motion connection with said cam means, and a passageway between said recessed plug and said outlet opening.
9. In combination, a valve body having a valve seat, a valve member normally urged toward said seat, and means engaged by said valve member upon rotation thereof for raising said valve member above said seat, the engagement between said valve member and said raising means being such as to permit said valve member to return to said seat automatically until after a predetermined raised position has been attained, said raising means being adjustable to vary said predetermined raised position.
10. In combination, a valve body having a valve seat therein, a rotatable valve member normally urged toward said seat and having a
- depending cylindrical portion, a cam surface formed in the periphery of said cylindrical portion, said cam surface having a gradually sloping portion and a relatively steep sloping portion with a notched portion therebetween, and a cam pin projecting into said valve body and adapted to engage said cam surface for raising said valve member above said seat upon rotation thereof, the engagement of said pin and surface providing for automatic return of said valve member to said seat as long as said pin engages the relatively steep sloping portion of said cam surface.
11. In combination, a valve body having a valve seat therein, a rotatable valve member normally urged toward said seat and having a depending cylindrical portion, a cam surface formed in the periphery of said cylindrical portion, said cam surface having a gradually sloping portion and a relatively steep sloping portion, and a cam pin projecting into said valve body and adapted to engage said cam surface for raising said valve member from said seat upon rotation thereof, the engagement of said pin and surface providing for automatic return of said valve member to said seat as long as said pin engages the relatively steep sloping portion of said cam surface, and providing for maintenance of said valve in raised position upon engagement of said pin with the gradually sloping portion of said cam surface.
12. In a valve, a valve body having a valve seat therein, valve means cooperating therewith, cam means comprising a cam member carried by said valve means and projecting pin means positioned in said valve body for engaging said cam member to open the valve upon rotation of said valve means, said cam member having a sharply inclined camming surface and a relatively slightly inclined surface, said pin means engaging said sharply inclined surface upon initial rotational movement of said valve means, and spring means for closing said valve means when said pin means is engaged upon said sharply inclined surface, said spring means being ineffective to close said valve means when said pin means engages said slightly inclined surface whereby said valve means is maintainable in adjusted positions to vary the flow of fluid through said valve only after said slightly inclined surface moves into engagement with said pin means.
13. In a valve for controlling the supply of gas to a gas burner, a valve member, a seat for said valve member, spring means urging said valve member toward said seat, a cam engaging pin, a camming surface on said member adapted to be engaged by said pin upon rotation of said member to cam said member from fully closed to fully open position, said camming surface having a portion providing for automatic movement of said valve member to closed position under the influence of said spring means from positions less than a safe minimum open position of said valve member capable of maintaining sufficient flow of fuel through the valve to maintain the burner lighted, said cam pin having adjustable means for varying said safe minimum open position of said valve member.

HERBERT E. TOELLE.
